VENDING MACHINE

Benjamin S. Mahaffey, Chicago, Ill.

Application July 25, 1936, Serial No. 92,625

12 Claims. (Cl. 312—94)

This invention relates to vending machines. It has for its general object the provision of vending apparatus for articles which deteriorate through the action of air, such, for example, as 5 cigars, nut meats, etc.

One of the objects of the invention is to provide individual receptacles for each sales unit, in which the article is maintained in a non-oxidizing atmosphere until dispensed.

Another object of the invention is to maintain 10 the article in individual chambers in a vacuum, to utilize the vacuum for assisting in holding the chambers closed in a fluid-tight manner, and for mechanically breaking the vacuum through the intermediary of an inserted coin for opening the 15 chamber and discharging its contents.

Since the operating structure is mechanically useful regardless of the adjunctive use of vacuum, the invention has for another of its objects the 20 provision of a vending machine having the novel structural characteristics and operative sequences such as will be disclosed in the following specification and illustrated in the accompanying drawings, in which:

Figure 1 is a side section view of a vending 25 machine, parts being broken away, illustrating the principle of the present invention;

Figure 2 is a section taken along the line 2—2 of Figure 1;

Figure 3 is a section taken along the line 3—3 of Figure 1;

Figure 4 is a vertical section through one of the receptacles;

Figure 5 is a plan view of one of the receptacles 35 or holders in a modified form of the invention;

Figure 6 is a section taken along the line 6—6 of Figure 5; and

Figure 7 is a fragmentary section showing the 40 relation of the supporting ledge to the upper frame only of the lowermost vending unit.

Referring now in detail to the several figures and first advertiring to that form illustrated in Figures 1 to 4, inclusive, the numeral 1 represents in general a cabinet having a relatively tall 45 stack casing 2 and a base portion 3, which is useful for holding the empty receptacles as they are displaced from the stack in a manner presently to be described.

Within the stack casing is a stack 4 constituted 50 by a vertical tier of receptacles 5. One of these receptacles is shown on an enlarged scale in Figure 4 and consists of a body portion 6 defining a chamber 7, the lower face of which is open, the receptacle being provided with a bottom closure 8 preferably hinged as at 9 and fitting in a fluid-

tight manner against the lower face of the body portion 6. To facilitate the sealing function of the closure a gasket 10 may be placed between the cooperating faces of the body portion and closure.

The lowermost receptacle 11 is supported by 5 ledges 12 on opposite sides and slide like a drawer upon said ledges. The other receptacles rest one upon another and upon the lowermost receptacle 11, the closure 8 of which, excepting that of the lowermost receptacle being supported in closed position by the receptacle next underlying. In the event that the receptacles are evacuated, the pressure of the atmosphere also assists in holding the closures tightly against the receptacles. It 10

will be observed from Figure 1 that there is nothing to hold the closure 8 of the lowermost receptacle closed and so it lies open in an inclined position determined by its engagement with the stop 14 which extends inwardly from the front end of the cabinet. All of the receptacles in the stack 15 will successively go to the position occupied by the lowermost receptacle 11, the closures when in inclined positions acting as chutes for discharging the contents of the receptacles which contents issue through the slot 15 into a cup 16, from 20 which they are gathered in the hand.

Coin controlled means is provided for pushing the lowermost or empty receptacle out of the way and bringing another receptacle from the stack 25 into a position in which its contents may be discharged. The coin controlled apparatus illustrated here consists of a guide 17 and a slide 18. The slide as shown has a downwardly extending end piece 19 within the cabinet in a position to 30 engage with and push the lowermost receptacle 11. When a coin is inserted in the slot 20 and the slide is pushed inwardly, the coin presses against 35

the bulge of the spring 19 forcing it down and throwing the end 21 below the plane of the slide 40 18 and out of engagement with the slide so that the latter can be freely pushed. When the slide is pushed in, to its fullest extent, the lowermost receptacle 11 takes the position shown in dotted lines at 22 and then falls empty into the base of 45 the cabinet. The other receptacles of the stack are guided for vertical fall by means of vertical guide rails 23 which terminate about in the plane of the top face of the lowermost receptacle and being deprived of the support of the lowermost 50 receptacle, may descend together until the receptacle at the bottom occupies the vacated space, resting upon the ledges 12. In the event that the chambers 7 are to be under vacuum, valve controlled ports 24 are provided each closed by a 55

valve 25 carried by a hinged valve plate 26 which closes the valve by gravity. The lower end 27 of the valve plate projects below the plane of the bottom of the receptacle in a position to be engaged by the receptacle next below when the latter is horizontally displaced so that the displaced receptacle acts to open the valve of the receptacle immediately above it and to release the vacuum. This leaves the closure 8 free to drop open by gravity just as soon as the supporting receptacle has been pushed from beneath it.

The means for evacuating the chambers 7 does not concern the invention. The vending machine may be serviced by removing empty receptacles from the base replacing and replenishing the stack with fresh filled receptacles already evacuated at a central station. For the purpose of drawing a vacuum in the receptacles, they may be filled with the commodity to be vended, closed, and a number of them at one time placed within a suitable chamber from which the air may be drawn by any convenient and known instrumentalities.

Referring now to Figures 5 and 6, the receptacles are substituted by frames 28, each consisting of a three sided member formed with upper and lower halves 29 and 30 hingedly joined as at 31 and coming together to form a fluid-tight joint 32. Both the top and bottom halves 29 and 30 are formed in their contiguous faces with matching channels 33 and 34, which together form a closed conduit 35. Said conduit communicates with a port 36 controlled by a valve 37 on a hinged valve plate 38 similar in construction to the valve plate shown in connection with that form of the invention illustrated in Figure 4. The front edge of the frame is open as indicated at 39 in Figure 5. The frame 26 has side lugs 40 and 41 formed with indentations 42 and 43 embracing vertical guides which may be similar in all respects to the guide rails 23 shown in Figure 2. The frames are adapted each to receive and hold a bag or package 44 of the article to be vended. The bag 44 is preferably of some gas-tight material such for example as "cellophane" and it may be formed by a piece of sheet material folded along the edge 45 and having its three free edges pasted together, but imperfectly. The three free edges are held clamped between the top and bottom members of the frame and extending into the conduit 35. A vacuum is drawn on the conduit 35 and due to the imperfect sealing of the free edges of the bag the interior of the bag will be evacuated. The operation of this form of the invention is essentially like that form first described. The push rod engages the lowermost frame shoving it out from beneath the stack. The stack of the frames then descends by gravity until the next lowest frame occupies the vacated position. As shown in Figure 7, the ledges 12 extend under the lugs 40 and 41 supporting the vending unit by the upper frame only, leaving the lower frame free to drop. In the course of its horizontal travel, the lowermost frame contacts the valve plate 38 opening the valve 37 and releasing the vacuum. When the lowermost frame is entirely out of the way, the lower half of the frame drops against the stop 14, the bag sliding out along the lateral edges of the inclined bottom member and discharging at the outside of the apparatus.

It will be understood to those skilled in the art that the above described structures are merely illustrative of a broad inventive principle which can find its realization in any number of mechan-

ical embodiments. It will therefore be understood that the details of construction as shown and described are merely by way of example and not to be construed as limiting the scope of the appended claims.

What I claim is:

1. Vending apparatus comprising a stack of receptacles resting one upon the other, each having a closure at the bottom, which closure except that of the lowermost receptacle being supported in closed position by the adjacent underlying receptacle, means for supporting the lowermost receptacle with freedom to be slidably displaced from beneath the others of the stack, said supporting means being in non-supporting relationship to the closure of the lowermost receptacle, operating means for displacing the lowermost receptacle from beneath said stack at the same time withdrawing its support from the bottom closure of the next lowermost receptacle whereby the said next lowermost receptacle drops into the position vacated by the lowermost receptacle discharging its contents through the opening uncovered by its unsupported closure.

2. Vending apparatus comprising a stack of receptacles each having a hinged closure at the bottom, which closures except that of the lowermost receptacle being supported in closed position between adjacent underlying receptacles, means supporting the lowermost receptacle with freedom to be slidably displaced from beneath the others of the stack, said supporting means being in non-supporting relationship to the bottom of the lowermost receptacle, operating means for displacing the lowermost receptacle from beneath said stack and simultaneously withdrawing its support from the bottom closure of the next lowest receptacle, permitting said next lowest receptacle to drop into the position vacated by the lowermost receptacle, discharging its contents through the opening uncovered by its unsupported closure.

3. Vending apparatus comprising a stack of receptacles each having a hinged closure at the bottom which closures except that of the lowermost receptacle are supported in closed position by the adjacent underlying receptacle, means for supporting the lowermost receptacle with freedom to be slightly displaced from beneath the others of the stack, said supporting means being in non-supporting relationship to the bottom of the lowermost receptacle, operating means for displacing the lowermost receptacle from beneath said stack permitting the stack to fall until the next lowest receptacle occupies the position vacated by the lowermost receptacle, said supporting means being in non-supporting relationship to the closure of the lowermost receptacle whereby said closure swings open, a stop for halting said closure in an inclined open position constituting said closure a chute along which the contents of said receptacle are discharged.

4. Vending apparatus comprising a stack of receptacles each having a hinged closure at the bottom, and the bottom of each including the closure except that of the lowermost being supported in closed position by the one beneath supplemented by atmospheric pressure, means supporting the lowermost receptacle with freedom to be displaced from beneath said stack, said supporting means being in non-supporting relationship to the bottom of the lowermost receptacle, operating means for displacing the lowermost receptacle from beneath said stack thus withdrawing support from the bottom of the next lowermost receptacle permitting it to drop into

the position vacated by the lowermost receptacle, said operating means simultaneously effecting the withdrawal of atmospheric pressure as an auxiliary support for the closure of the lowermost receptacle permitting it to open for the discharge of its contents.

5. Vending apparatus comprising a stack of receptacles each having a hinged closure at the bottom and the bottom of each excepting the lowermost being supported in closed position by the one beneath, means supporting the lowermost receptacle with freedom to be displaced from beneath said stack, said supporting means being in non-supporting relationship to the bottom of the lowermost receptacle, said receptacles being individually under vacuum, each receptacle having a port communicating therewith and a valve for said port for retention of the vacuum within said receptacle, and operating means for displacing the lowermost receptacle from beneath said stack, thus withdrawing the support from the bottom of the next lowermost receptacle permitting it to drop into the position vacated by the next lowermost receptacle, said operating means simultaneously effecting the opening of the valve of the lowermost receptacle releasing the vacuum and permitting the bottom closure to open for discharging the contents of said receptacle.

6. Vending apparatus comprising a stack of receptacles each having an openable closure at the bottom, and the bottom of each except the lowermost being supported in closed position by the one beneath, means for supporting the lowermost receptacle with freedom to be displaced from beneath said stack, said supporting means being in non-supporting relationship to the bottom closure of the lowermost receptacle, a valve controlled port communicating with the interior of each receptacle, a plate for each valve extending below the plane of the bottom of the receptacle with which it is associated, and operating means for displacing the lowermost receptacle from beneath said stack thus withdrawing the support from the bottom of the next lowermost receptacle, permitting it to drop into the position vacated by the lowermost receptacle, the lowermost receptacle when displaced contacting the valve plate of the adjacent upper receptacle opening the valve and discharging the vacuum permitting the closure to open when the said next to lowest receptacle becomes the lowest receptacle.

7. Vending apparatus comprising a stack of receptacles, the receptacles being freely descendible to the position normally occupied by the lowermost receptacle, each receptacle of the stack having an openable bottom and the bottom of each excepting the lowermost being supported in closed position by the adjacent underlying receptacle, means supporting the lowermost receptacle with freedom to be displaced from beneath said stack, said means supporting the lowermost receptacle in such position as to permit the bottom to open, and operating means for displacing the lowermost receptacle from beneath said stack permitting the next lowermost receptacle to drop into the position vacated by the lowermost receptacle, in which position its bottom being unsupported opens, a stop arresting the opening movement of the bottom to hold it in inclined position, said bottom then functioning as a chute in discharging the contents of the receptacle.

8. Vending apparatus comprising a stack of receptacles, each having an openable closure at the bottom, and the bottom of each except the lowermost being supported in closed position by the one beneath, means for supporting the lower-

most receptacle with freedom to be displaced from beneath said stack, said supporting means being in non-supporting relationship to the bottom closure of the lowermost receptacle, a valve-controlled port communicating with the interior of each receptacle, a plate for each valve extending below the plane of the bottom of the receptacle with which it is associated, and operating means for displacing the lowermost receptacle from beneath said stack thus withdrawing support from the bottom of the next lowermost receptacle, permitting the stack to drop with the said next lowermost receptacle into the position vacated by the lowermost receptacle, the now lowermost receptacle when displaced contacting the valve plate of the adjacent superposed receptacle, opening the valve and discharging the vacuum permitting the closure to open, a stop arresting the opening movement of the bottom closure to hold it in an inclined position, said bottom closure then functioning as a chute in discharging the contents of the receptacle.

9. Vending machine comprising a stack of individual vending members, each comprising hinged parts, each part being a frame open at one side with the sides of said frames having matching engaging surfaces, adapted to clampably receive and hold between them certain edges of a bag of impervious material, a support for said stack engaging the lowermost member of said stack, said support and said members being so related that said support engages the upper frame only leaving the lower frame of the lowermost member free to open, means for displacing the lowermost member from beneath said stack thus withdrawing support from the next lowermost member, permitting it to drop into the position vacated by the lowermost member, thus withdrawing the support from the lower frame of the now lowermost member permitting it to swing open for discharging said bag.

10. Vending machine comprising a stack of individual vending members, each comprising hinged parts, each part being a frame open at one side, with the sides of said frame having matching engaging surfaces, said surfaces being provided with matching channels adapted to be evacuated, a port communicating with said channels and a valve controlling said port adapted to be opened upon occasion for releasing the vacuum, a bag of impervious material having certain imperfectly sealed edges clampably held between the matching faces of said frame and in communication with said channels, a support for said stack engaging the lowermost member of said stack, said support and members being so related that said support engages the upper frame only of said members when they become successively the lowermost member of the stack, a plate for each member upon which said valve is mounted, said plate extending below the plane of the bottom of the member with which it is associated, and operating means for displacing the lowermost member from beneath said stack thus withdrawing the support from the next lowermost member permitting it to drop into the position vacated by the lowermost member, the lowermost member when displaced contacting the valve plate of the adjacent superposed member opening the valve and discharging the vacuum, permitting the lower frame to open to discharge the contents of the vending member.

11. Vending machine as claimed in claim 10, including a stop arresting the opening movement of the lower frame of the lowermost member to

hold it in an inclined position, said frame functioning as a chute in discharging the bag from said member.

12. Vending apparatus comprising a stack of individual vending members of the type which hold under vacuum the product to be vended, said vending members each having an openable part normally held closed by vacuum and which opens when the vacuum is relieved permitting the discharge of the said product, each of said vending members having a vacuum relieving element en-

gaged by the vending member immediately below it when the latter is displaced, for relieving the vacuum in the vending member whose said element is thus engaged, and means for displacing the lowermost vending element from beneath said stack whereby the next lowest member becomes the lowest, its vacuum is relieved, its openable part opened, and the product permitted to discharge.

BENJAMIN S. MAHAFFEY. 10
